UNITED STATES PATENT OFFICE.

KHURSEDJI MANEKJI TATA, OF NAVSARI, NEAR BOMBAY, INDIA.

POCKET-KNIFE.

SPECIFICATION forming part of Letters Patent No. 453,296, dated June 2, 1891.

Application filed October 1, 1890. Serial No. 366,768. (No model.)

To all whom it may concern:

Be it known that I, KHURSEDJI MANEKJI TATA, of Navsari, near Bombay, India, have invented a new and useful Improvement in 5 Knife-Blades, of which the following is a full, clear, and exact description.

My invention relates to an improvement in knife-blades, and especially to blades of pocket-knives, and has for its object to so construct the blade that when sharp there will be less likelihood of cutting the fingers when used by a careless or inexperienced person or by a child than when an ordinary knife is used.

The invention consists in the novel construction and combination of the several parts, as will be hereinafter fully set forth, and pointed out in the claim.

Reference is to be had to the accompanying drawings, forming a part of this specification, 20 in which similar figures and letters of reference indicate corresponding parts in all the views.

Figure 1 is a side elevation of the knife-blade, illustrated as pivoted to a handle. Fig. 25 2 is a transverse section on line 2 2 of Fig. 1. Fig. 3 is a similar section on line 3 3 of Fig. 1. Fig. 4 is a side elevation of the blade detached, illustrating a slight modification in its construction; and Fig. 5 is a side elevation of a 30 portion of a blade, illustrating a further modification in its construction.

The blade 10 is provided with a series of recesses 11 in one edge, separated by blunt partitions 12, which partitions are of a width corresponding to the width of the blade. The longitudinal edges of the recesses 11 are beveled and sharpened to constitute cutting-edges, as illustrated at a.

Any number of recesses provided with cutting-edges may be formed in the knife-blade, 40 two being illustrated in Fig. 1; but in Fig. 4 the blade is illustrated as provided with recesses formed at intervals throughout the entire length of the body of the blade.

In Fig. 4 a roughened or file surface 13 is 45 formed upon one side of the blade at its outer end, and in both Figs. 1 and 4 the outer ends

of the blades are rounded and more or less blunt instead of being pointed, as is customary.

In the form of blade illustrated in Fig. 1, 50 between the outer end and the outer recess 11 therein, the inner edge of the blade is beveled and sharpened in the ordinary manner, and upon the beveled face of the blade at the outer end a file-surface 14 is produced, corresponding to the file-surface 13 of the form 55 of blade illustrated in Fig. 4. The recesses 11 are made sufficiently wide to permit the cutting-edges a located between them to be used for trimming the nails and for sharpening pencils; but the recesses may be made shorter or longer than illustrated, if in practice it is found desirable.

It will be observed that as the cutting-edges are located somewhat near the longitudinal 65 center of the blade the partitions 12 between the cutting-surfaces serve as guards, and that it is almost impossible to use the knife so carelessly as to injure the user. The file combined with the blade renders the improved 70 blade especially desirable for manicure purposes.

It will be understood that the recesses 11 may be given any desired shape—as, for instance, they may be curved or arched at their 75 cutting-surfaces, as shown at a' in Fig. 5.

Having thus described my invention, I claim as new and desire to secure by Letters Patent—

As an improved article of manufacture, a 80 knife-blade provided with a series of rectangular recesses in one edge separated by partitions having blunt outer edges, the inner walls of the said recesses being sharpened to form cutting-edges, as and for the purpose 85 specified.

In testimony that I claim the foregoing as my invention I have signed my name, in presence of two witnesses, this 1st day of August, 1890.

KHURSEDJI MANEKJI TATA.
